(57) CLAIM

The ornamental design for a dual-sole shoe with red outsole patch as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design of a dual-sole shoe with orange outsole patch, in which the outsole patches are hatched using the USPTO convention of diagonal cross-hatched lines for orange (e.g., Pantone 148-Pantone 154, any one of Pantone 156-Pantone 168, any one of Pantone 172-Pantone 175, any one of Pantone 470-Pantone 475, any one of Pantone 486-Pantone 489, any one of Pantone 712-Pantone 721, Pantone 804, Pantone 811, any one of Pantone 1205-Pantone 1685; or any one of RAL 2000-RAL 2013);

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1;

FIG. 8 is a perspective view of another embodiment of our new design of a dual-sole shoe with orange outsole patch;

FIG. 9 is a first side view of the design of FIG. 8;

FIG. 10 is a second side view of the design of FIG. 8;

FIG. 11 is a top view of the design of FIG. 8;

FIG. 12 is a bottom view of the design of FIG. 8;

FIG. 13 is a front view of the design of FIG. 8; and,

FIG. 14 is a back view of the design of FIG. 8.

The broken lines illustrating the upper, the half moon patch, the groove, and the heel stripe in the above described depict environment and form no part of the claimed design.
